(57) **CLAIM**

The ornamental design for a rear lamp on vehicle, as shown and described.

DESCRIPTION

FIG. 1 is a front view of a rear lamp on vehicle showing our new design;

FIG. 2 is a top view thereof;

FIG. 3 is a right view thereof;

FIG. 4 is a left view thereof;

FIG. 5 is a rear view thereof;

FIG. 6 is a bottom view thereof; and,

FIG. 7 is a perspective view thereof in context.

The overexposed or faded features of the motor vehicle exterior are provided for the purpose of illustrating portions of the article that form no part of the claimed design.
